UNITED STATES PATENT OFFICE.

HAROLD B. SANKEY, OF WOLVERHAMPTON, ENGLAND.

Sheet-Metal Road Wheel.

Original application filed November 11, 1919, Serial No. 337,361. Divided and this application filed February 27, 1922. Serial No. 539,574.

To all whom it may concern:

Be it known that I, HAROLD BANTOCK SANKEY, captain, R. F. A., a subject of the King of Great Britain, and residing at Wolverhampton, in the county of Stafford, England, have invented certain new and useful Improvements in Sheet-Metal Road Wheels, of which the following is a specification.

This invention relates to sheet metal wheels of the disc type in which the disc is set out a considerable distance from the mid plane of the wheel, and consists in forming the disc in two parts a middle part and an outer annular part, a laterally projecting flange being formed on the inner part at its periphery. The inner edge of the outer part is secured to the periphery of the inner part in any suitable manner.

This application is a division of my prior application, Serial No. 337,361, filed November 11, 1919.

A convenient practical form of the invention is illustrated by the drawing herewith.

As shown in the drawing, the wheel comprises an inner or middle disc member *p* and an outer disc member *q*. The inner disc member is bolted at its inner edge to a flange *r* of the wheel hub and has, at its outer periphery, a flange *s*. The outer disc member is secured to the inner disc member by

having formed upon its inner edge a flange *t* which is bolted to the flange *s*. The outer disc member has also a flange *u* which carries the wheel rim *v*.

Having fully described my invention, what I claim and desire to secure by Letters Patent, is:—

1. A sheet metal disc wheel comprising an outer annular disc member, an inner disc member and a flange at the outer edge of said inner disc member, and means by which said outer disc is secured at its inner edge to said inner disc member.

2. A sheet metal disc wheel comprising an outer disc member, a flange at the outer edge of said outer disc member, an inner disc member and a flange at the outer edge of said inner disc member, and means by which said outer disc member is secured at its inner edge to said inner disc member.

3. The combination with a hub having a barrel and flange, of a central member arranged upon said hub and connected thereto, the outer edge of said member being turned laterally, and a disk having its inner edge turned laterally and connected to the edge of said member.

In witness whereof I have hereunto signed my name this 23rd day of February, 1921.

HAROLD B. SANKEY.
